[57] CLAIM

The ornamental design for a food grinder, substantially as shown and described.

DESCRIPTION

FIG. 1 is a side elevational view showing the left side of a food grinder embodying my new design;

FIG. 2 is a front elevational view thereof;

FIG. 3 is a top plan view thereof; and

FIG. 4 is a bottom plan view thereof.

The side view opposite that shown in FIG. 1 is a mirror image thereof. The rear view opposite that shown in FIG. 2 is substantially the same except where the cord extends therefrom and except for the appearance of a line within the cover at the top, which line is indicated in FIG. 3.

FIG. 1.

FIG. 2.

FIG. 3.

FIG. 4.
